BACK REST FOR BLEACHER SEATS

Filed August 8, 1925

FIG. 2-

FIG. 3-

Inventor

FIG. 4-

J. J. Byberg
By Watson E. Colman
Attorney

UNITED STATES PATENT OFFICE.

JONAS J. BYBERG, OF SILVERTON, OREGON.

BACK REST FOR BLEACHER SEATS.

Application filed August 8, 1925. Serial No. 49,074.

The object of this invention is to provide a back rest that can be quickly and easily attached to any seat which is not provided with a back rest as, for instance, the bleacher seats of grandstands, circus seats, etc.

A further object is to provide a device of this character which is of such simple construction that it may be sold at such a low price that it may be cast aside when the period of use is ended.

A still further object is to provide a back rest which is light, compact, which is adjustable to different seats on which it may be used, and which is also adjustable to different angles of inclination.

My invention is illustrated in the accompanying drawing, wherein:—

Figure 1 is a sectional view through a seat with my back rest applied thereto, the back rest being shown in end elevation;

Figure 2 is a front view of the back rest and of the seat;

Figure 3 is a rear view of the back rest and rest;

Figure 4 is a perspective view showing the seat engaging hook and the back rest supporting cord.

Referring to this drawing, it will be seen that I have shown my back as applied to a

bleacher seat A which is meant to be illustrative of any seat without a back. My device comprises a back board 10 which may be made of any suitable material and of any degree of lightness which will give the proper strength. Attached to the back adjacent its upper end is the transverse cross bar 11 which projects beyond the back on each side.

Extending across the rear face of this back rest is a cord, chain or other flexible member 12 which, adjacent the ends of the cross bar 11 or brace, passes through eyes 13. The ends 14 of this cord 12 are flexible and in the use of the device extend toward the forward edge of the seat and thus act as a support for the back rest and the ends of these portions 14 of the cord 12 are knotted at a plurality of points, as at 15.

Coating with these knots and disposed in the portion 14 is a double hook 16, one bill of which is large enough to engage over the forward edge of the seat A. The upper or small bill of this S-shaped hook is relatively small and in effect just large enough for the passage of the cord or other flexible connection 14 but not large enough for the

passage of the knot 15. As a consequence when strain is placed upon the back as, for instance, by a person leaning against it, the portions 14 of the cord will tighten and the knots will draw up against the hooks 17 and the back will be fully supported against rearward pressure.

It will be obvious that if the seat is relatively wide, the hooks will be engaged with the outermost knots 15 but if the seat A is relatively narrow the hooks will be engaged with the innermost knots 15, and that if it is necessary further knots may be tied in the flexible member so as to place the hooks still nearer to the back. It is obvious that the back may be inclined at any desired angle to the seat A and held at this inclination by properly adjusting the hooks 17 upon the portions 14 of the supporting cord. The lower end of the back board can be moved forward or backward, depending on the angle of inclination desired, and my construction enables the back rest to be adjusted to different widths of seats and to different desired angles and positions.

I do not wish to be limited to any specific material for the back rest, nor to a specific form of flexible member 12 and 14.

I claim:—

1. A back rest for seats comprising a back proper, a flexible member extending across the back and then adapted to extend downward and forward, the flexible member adjacent its free ends being formed with a series of knots, double hooks coating with said free ends and adapted to engage the forward edge of the seat, each hook being formed with a relatively large seat engaging bill, and a relatively small member engaging bill.

2. A back rest for seats comprising a back proper, a cord extending across the back having two free end portions adapted to extend downward and forward, the cord adjacent each of its free ends being formed with a knot, hooks coating with said free ends and adapted to engage the forward edge of the seat, each hook being formed with a seat-engaging bill and a rope-engaging knot-engaging portion.

3. A back rest for bleacher seats comprising a back proper, a cross bar attached to the back and having eyes adjacent its ends, a flexible member passing through said eyes and adapted to extend downward and for-

ward therefrom, the downward and forward portions having knots at their extremities, an a double hook formed to provide a large bill and a small bill, the large bill being adapted to engage the forward edge of a seat and the small bill to receive said flexible member but being smaller than the knots.

4. A bleacher seat back rest comprising a back, a transverse brace attached to the back, 10 a cord passing across said brace and connected thereto and having end portions extending beyond the brace on each side, the extremities of the end portions being knotted at a plurality of points, and a double hook 15 mounted upon each end of the cord, each hook consisting of a relatively large hook-shaped portion and a relatively small hook-shaped portion, the latter being small

enough to slide upon the cord but too small to permit the passage of the knots. 20

5. A back rest for seats comprising a back proper, cords extending downward from the back adjacent the upper end thereof, and hooks mounted upon the ends of the cords, each hook being formed to provide a relatively large hook portion adapted to engage beneath a seat, and a relatively small eye with which the corresponding cord is loosely engaged, each cord and the corresponding hook being formed with coacting 25 means whereby the hook may be adjusted nearer to or further from the back. 30

In testimony whereof I hereunto affix my signature.

JONAS J. BYBERG.
